(57) **CLAIM**

The ornamental design for a display screen with an animated graphical user interface, as shown and described.

DESCRIPTION

FIG. 1 is a view of a first transitional image of a display screen with an animated graphical user interface.

FIG. 2 is a view of a second transitional image of a display screen with an animated graphical user interface; and, FIG. 3 is a view of a third transitional image of a display screen with an animated graphical user interface.

The appearance of the transitional image sequentially transitions between the images shown in FIG. 1-3. The process or period in which one image transitions to another image forms no part of the claimed design.

The long-short-long-dashed broken line is included for the purpose of illustrating a display screen and forms no part of the claimed design. The evenly-dashed broken line is included for the purpose of illustrating an animated graphical user interface and forms no part of the claimed design.
